UNITED STATES PATENT OFFICE.

C. AXEL BACKSTROM, OF TRENTON, NEW JERSEY, ASSIGNOR TO THE BACKSTROM CENTRIFUGAL SEPARATOR COMPANY, OF NEW JERSEY.

CENTRIFUGAL LIQUID-SEPARATOR.

SPECIFICATION forming part of Letters Patent No. 368,049, dated August 9, 1887.

Application filed March 11, 1887. Serial No. 230,518. (No model.)

To all whom it may concern:

Be it known that I, C. AXEL BACKSTROM, a citizen of the United States, residing at Trenton, in the county of Mercer, State of New Jersey, have invented certain new and useful Improvements in Centrifugal Liquid-Separators, of which the following is a specification, reference being had therein to the accompanying drawings.

10 This invention has relation to centrifugal liquid separators; and although hereinafter described as to its construction and operation in connection with the separation of cream from milk, the invention is not limited to any 15 particular use of the same.

Among the objects of the invention are to control the quality of a lighter constituent while the machine is in operation, to vary the 20 quality of both constituents at will while the machine is in operation, and to provide a separating-bowl of such construction and having such accessories as will accomplish the objects in view.

Heretofore the quality of a lighter constituent has been controlled by changing the 25 capacity of the port or orifice through which the heavier constituent has been delivered; but said port or orifice having been located in a wall of the bowl, it has been necessary, in 30 order to change the capacity of said port, (to increase or decrease the amount of the heavier constituent delivered from the bowl,) to stop the rotation of the bowl and the operation of the machine.

35 This is exceedingly objectionable because of the loss of time incurred. It therefore follows that the provision of any means for controlling or varying at will the quality of the lighter constituent delivered from the machine is a matter of material value, not only by reason of the fact that a lighter constituent, having an almost absolute purity, (that is, almost absolutely free from any mixture of the heavier constituent,) can be secured, but, 40 as is sometimes desired, such lighter constituents may be more or less impregnated or mixed with the heavier. In fact, if while during the operation of the machine the lighter constituent is by proper test shown to contain

a material percentage of the heavier, (which 50 to a greater or less degree has heretofore been the actual fact,) any material quantity or excess of the heavier constituent can by my invention be separated from the lighter constituent, so that it shall be delivered from the 55 machine in a practically pure state. The more or less perfect and free delivery of the heavier constituent after it has been separated from the lighter will determine the quality of the lighter.

50 My invention consists of certain features of construction hereinafter described, and particularly pointed out in the claims.

Referring to the drawings, Figure 1 is a side elevation, with portions in section, of a centrifugal machine constructed in accordance with my invention. Fig. 2 is a similar view of portions of Fig. 1, provided with a discharge conductor for the heavier constituent.

Like letters indicate like parts in both figures.

60 A represents a portion of any suitable framework for the operative parts of the machine.

B represents the spindle, upon which the separating-bowl C is mounted in any suitable 65 manner. The bowl C has a depression or neck, C', in the bottom thereof, and at the bottom of the neck is a port, C'', for the discharge of a lighter constituent. C''' represents the supply-chamber of the bowl, and from said chamber 70 there extends a supply-pipe, C'', radially and near to the inner periphery of the bowl. In this instance a shield or cone, C'', is formed or may be mounted on the supply-chamber and projects upwardly to or above or through a 75 central opening in the top of the bowl. Upon the top of the bowl is formed an annular chamber, C'', from which there depends a pipe, C'', which terminates near the inner periphery of the bowl and serves the purpose of conducting 80 the heavier constituent upwardly into the annular chamber C''. A cream-receiving bowl, D, is mounted upon the standard A and has a discharge-spout, D''. There is cast integrally with the bowl D a stud or standard, D'', which 85 has secured to it by a pivot, D'', an arch or curved arm, D'', said arm being retained in a 90 position over the bowl by a pin, D''. The arch

or arm D¹ is provided with a pocket, D⁶, arranged centrally over the bowl. Within the pocket is a sleeve, E, having an annular groove, E', for the reception of a set-screw, E', which 5 serves the purpose of retaining the sleeve within the pocket D⁶. The sleeve is bored for the reception or connection of a feed-pipe, F, having a stop-cock or valve, F', and is provided with a socket, E³, which serves the purpose of supporting a discharge-conductor, G.

The conductor G is provided with a stop-cock or valve, G', and is capable of longitudinal movement in the socket E³. In Fig. 2 is illustrated a screw-threaded connection, 15 whereby the longitudinal movement of the conductor is made regular. The provision of a capability of longitudinal movement enables the conductor to be extended into the annular chamber a greater or less distance, as desired, 20 while the rotatable connection of the sleeve with the arch or arm permits of a rotation of the conductor, so as to present the delivery end thereto at any desired point around the machine, as indicated by dotted lines X, Fig. 2. 25 In this instance a flexible hose or other extension, G², connects with the discharge-pipe, and may communicate with any desired receptacle for the heavier constituent.

This being the construction, the operation 30 is as follows: It is well known that in separating cream from milk in a centrifugal machine the milk, being the heavier constituent, collects at a point farther from the center of motion of the rotating bowl than the cream, and 35 that the cream naturally collects in an annular body inside of the body of the milk. The annular body of cream collects in a vertical plane substantially conforming with that of the wall of the neck C' of the bowl, and falls by 40 gravity into said neck, from whence it is delivered through the port C² into the cream-receiver D, and from thence through the spout D' thereof into any suitable receptacle. The milk is supplied through the pipe F to the 45 supply-chamber C¹, and from thence it passes through the pipe C' into the bowl. The discharge-pipe C' conducts the skimmed milk into the annular chamber C⁶. The delivery-conductor G is projected into the annular chamber C⁶ and gathers, conducts, and delivers the 50 skimmed milk from the machine. Now, in case any of the skimmed milk should be spattered, thrown, or otherwise detached from the body of skimmed milk in the annular chamber C⁶, it is received by the cone or shield C' and directed again into the supply-chamber of the bowl, whereby the said skimmed milk is 55 prevented from becoming mixed with the annular body of cream within the bowl. 60 The relative arrangement of the parts required for the collection of the skimmed milk (herein shown) is important in so far as it involves a disposition of the heavier constituent above the lighter when within the bowl, for the reasons above given; but the same is not 65 broadly claimed in this application, as it forms

the subject-matter of a companion application pending herewith. The provision of a cone or shield is also a material improvement, as it renders the subsequent admixture of the once separated constituents absolutely impossible, and in this regard contributes to the production of a practically pure lighter constituent. Now it is apparent that, as hereinbefore generally stated, if the delivery-conductor G is adjusted within the annular chamber C⁶, so as to collect therefrom its fullest capacity of skimmed milk, and if the valve G' of the conductor be entirely open (it being understood that the supply is properly regulated to the capacity of the bowl by means of the valve F') the cream will be practically free from skimmed milk, and that if under the same circumstances the valve G' be partially closed more or less of the skimmed milk 85 within the bowl may become mixed with and delivered with the cream. Therefore the quality of the lighter constituent is entirely under the control of the operator, and by reason of the accessibility of the discharge-conductor 90 and its controlling-valve, both of which are relatively fixed, such a control of the quality of the lighter constituent may be exercised while the machine is in operation.

It seems to be essential that the delivery-conductor should be continuous and unbroken from one end thereof (which is located at that portion of a separating-bowl at which the heavier constituent is collected during the operation of the bowl) to a point outside of the machine and accessible to the operator.

Certain features of construction herein shown and described are not claimed, as they form the subject-matter of another application pending herewith.

Having described my invention and its operation, what I claim is--

1. In a centrifugal machine, and in combination with the supply-chamber thereof, an annular chamber arranged at the top of the bowl and having communication with the portion of the bowl near its inner periphery, and a shield arranged between the supply-bowl and the annular chamber, substantially as specified.

2. A bowl for a centrifugal machine provided with an upper annular chamber for a heavier constituent, a lower discharge-port for a lighter constituent, and a shield arranged between said chamber and port, whereby direct access of a heavier constituent to the portion of the bowl occupied by the lighter constituent is prevented, substantially as specified.

3. The combination of the separating-bowl C, the cream-bowl D, having the standard D², the pivoted arch or arm D¹, the sleeve E, and the delivery-conductor G, substantially as specified.

4. The combination, with the bowl C, of the arch or arm D¹, having the pocket D⁶, the sleeve E, having the socket E³ and the delivery-conductor G, and means for closing the

sleeve within the pocket, substantially as specified.

5. The combination of the arch or arm D⁴, having the pocket D⁶, the apertured sleeve E, having the socket E³ and conductor G, and the supply-pipe F, communicating with the sleeve, substantially as specified.

In testimony whereof I affix my signature in presence of two witnesses.
